UNITED STATES PATENT OFFICE.

ARCHIE R. FERGUSON, OF COLTON, WASHINGTON.

GRAIN SEPARATING AND VITRIOLIZING MACHINE.

No. 853,076.

Specification of Letters Patent.

Patented May 7, 1907.

Application filed April 6, 1906. Serial No. 310,813.

To all whom it may concern:

Be it known that I, ARCHIE R. FERGUSON, a citizen of the United States, and a resident of Colton, in the county of Whitman and State of Washington, have invented a new and Improved Grain Separating and Vitriolizing Machine, of which the following is a full, clear, and exact description.

This invention relates to improvements in machines for separating wild oats from wheat, barley, or other grain, the main object being to provide a means for treating the grain with a cleaning solution to kill the smut germs, thus promoting the growth of the grain.

Other objects of the invention will appear in the general description.

I will describe a grain separating and cleaning machine embodying my invention and then point out the novel features in the appended claims.

Reference is to be had to the accompanying drawings forming a part of this specification, in which similar characters of reference indicate corresponding parts in all the figures.

Figure 1 is a perspective view of a machine embodying my invention; Fig. 2 is a side elevation thereof; Fig. 3 is a sectional elevation; Fig. 4 is a detail in section showing a modification in the separating device; Fig. 5 is a detail indicating the mechanism for operating the vertical conveyer employed; and Fig. 6 is a sectional detail showing a portion of a screen shaking mechanism.

The main structure comprises a fanning mill substantially of the ordinary construction; that is, it consists of a casing 1 in which is arranged a rotary fan 2 having on its shaft a pinion 3 meshing with a gear-wheel 4 operated by a crank 5.

In the upper portion of the casing is a hopper 6, the opening 7 in the lower portion thereof being regulated by a valve-plate 8. Below the hopper are ordinary screens 9 below which are reversely inclined deflecting boards 10, 11, the board 10 being designed to direct the grain onto the board 11, from which the same passes underneath a head 12 onto a screen 13, which terminates at its outer end in a trough 14; and underneath the screen 13 is a board 15 open at its lower end, it being understood that the said screen 13 and board 15 are inclined.

Arranged upon the screen 13 is a flexible material 16 such for instance, as canvas, the

inner end thereof being secured to the board 11. The screen 13 and the board 15 have lateral motion, and for this purpose an eccentric 17 is attached to the fan shaft and is engaged by an eccentric ring 17^a from which a rod 18 passes to a crank lever 19 having a rod 20 which passes through an opening 21 to connection with a side member of the board 15. Below the parts 13 and 15 is a downwardly and forwardly inclined screen 22, to which vibratory motion is imparted by means of an eccentric on the fan shaft, having a rod connection 23, with an arm 24 on a rock-shaft 25, from which an arm 26 extends upward and inward and has a rod connection 27 with said screen 22. It will be noted that a frame in which are the screens and the parts 13 and 15, is connected to swinging hangers 28.

The angle of the screen 22 may be adjusted as desired, as the rear vertical posts of the casing are provided with perforations 29 for receiving pins 30 on which the screen frame may rest. Below the screen 22 are screening-boxes 31, which are here shown in the form of drawers. At the front of the casing and adapted to receive grain from the screen 22, is a horizontally disposed liquid holding trough 32, in which is a spiral conveyor 33, on the shaft of which is a sprocket-wheel 34, engaged by a sprocket chain 35, the said chain passing over a sprocket-pinion 36 on the fan shaft.

Extending over the receptacle 32 is a perforated spray-pipe 37, having a pipe connection 38 with a vessel 39, in which a cleaning liquid is to be placed, such for instance, as a solution of vitriol water, formaldehyde, or any other liquid solution that will kill the smut germ. The pipe 38 is provided with a valve 40, so that the supply of liquid may be cut off when desired or when the machine is to be used without the solution treatment.

The liquid receptacle 32 has an outlet 41 communicating with a vertical tube 42 in which a spiral conveyer 43 operates. The shaft 44 of the conveyer 43 passes through an opening in the upper closure of the tube 42, and is connected with a bevel-wheel 45, the said bevel-wheel meshing with a bevel pinion 46 mounted on a countershaft 47 to which is secured a sprocket-wheel 48 engaged by a chain 49, the said chain being operated from a sprocket pinion 50 on the fan shaft. At the upper end of the tube 42 there is a spout 51 for discharging grain into a box 52.

having an opening normally closed by a sliding gate 53, and attached to the lower end of the box 52 are hooks 54 for supporting a bag into which the grain is discharged from said box.

In operation, the wheat or other grain which is generally mixed with wild oats, passes from the hopper 6 onto the screens 9 and through the same to the boards 10 and 11, and thence to the screen 13; the oats will be held in a flat position by means of the canvas 16, and will roll down the screen into the trough 14 and then out of said trough; the wheat will pass through the openings of the screen 13 the board 15 and thence to the screen 22. By abrasion upon the grain passing through the screens and upon the boards, the smut will be removed therefrom, and the grain will pass from the screen 22 into the receptacle 32 where it will be treated with the liquid flowing from the container 39, and in passing through the receptacle 32 the grain will be thoroughly soaked, as it is well understood that thorough soaking can only take place after removing the smut.

The spiral conveyer 33 moves the grain into the tube 42 and the liquid passing into said tube 42 will leak out through an opening 55 in the lower end of said tube and into a pan 56, so that by this arrangement there will be practically no waste of the liquid, as it may be transferred from the pan 56 into the receptacle 39 and used again. The grain discharged into the tube 42 will be carried upward by the conveyer 43 and deposited in the box 52 from which it may be passed into a bag as before mentioned.

In the modification shown in Fig. 4, a step-like screen 57 is arranged over the board 15, which terminates in a trough 58. In this construction the grain and oats pass onto the screen and in sliding over the step-positions the oats will be vertically-ended and passed through the meshes of the screen onto the board 15, and then out through the trough 58; the wheat or similar grain being too large to pass through the screen, will fall upon the screen 22.

Having thus described my invention I claim as new and desire to secure by Letters Patent:—

1. A machine for the purpose specified,

comprising a casing, a hopper in the upper portion of the casing, screens arranged below said hopper, oppositely inclined boards underneath said screens, a vibrating screen below the boards, a trough at the outlet end of said screen, a flexible material arranged over the screen, a board underneath the vibrating screen, another vibrating screen below the first-named vibrating screen, a liquid receiving trough into which grain discharges from the last named screen, a perforated tube above said trough, a liquid receptacle for feeding liquid into said perforated tube, and means for conveying grain through said liquid receiving trough.

2. A machine for the purpose specified, comprising a casing, a rotary fan in the casing, a plurality of screens in the casing, a liquid receiver extending horizontally along the front of the casing at the lower portion, a perforated pipe over said receiver and extending substantially the entire length thereof, a liquid container having pipe connection with the said perforated pipe, a rotating, spiral conveyer in said receiver, a tube extended vertically along one side of the casing and communicating at its lower end with said receiver, the said tube having a perforation in its lower end, and a spiral conveyer in said tube.

3. A machine for the purpose specified, comprising a casing, a rotary fan in the casing, a plurality of screens in the casing, a liquid receiver extending across the front of the casing, a spiral conveyer in said receiver, a tube with which the receiver communicates, the said tube being extended upward and communicating at its lower end with the receiver, a spiral receiver in said tube, means operated from the fan shaft for imparting motion to the conveyer in the receiver, means operating from the fan shaft for imparting motion to the conveyer in said tube, and means operated from the fan shaft for oscillating certain of said screens.

In testimony whereof I have signed my name to this specification in the presence of two subscribing witnesses.

ARCHIE R. FERGUSON.
